UNITED STATES PATENT OFFICE.

GILBERT L. HUFF, OF HOLDENVILLE, OKLAHOMA.

VENDING-MACHINE.

1,276,923.

Specification of Letters Patent. Patented Aug. 27, 1918.

Application filed January 30, 1918. Serial No. 214,533.

To all whom it may concern:

Be it known that I, GILBERT L. HUFF, a citizen of the United States of America, residing at the city of Holdenville, county of Hughes, State of Oklahoma, have invented a certain new and useful Vending-Machine, of which the following is such a full, clear, and exact description as will enable any one skilled in the art to which it appertains to make and use the same, reference being had to the accompanying drawings, forming part of this specification.

My invention relates to a vending machine, and more particularly to a machine for vending thin articles, such as sheets of paper. The object of my invention is to provide a device of the class described, which will be simple and effective in operation and which will dispense but a single article at a time.

In the accompanying drawings, which illustrate one form of device made in accordance with my invention, Figure 1 is a front elevation; Fig. 2 is a side view; Fig. 3 is an enlarged horizontal section through a portion of my machine; Fig. 4 is a section taken on the line 4—4 of Fig. 3; Fig. 5 is a section taken on the line 5—5 of Fig. 6; Fig. 6 is a section taken on the line 6—6 of Fig. 5.

10 represents the back portion of the casing which is secured in vertical position by any suitable means, as for instance, the openings 11, shown in Fig. 5 of the drawings. 12 is the front portion of the casing, which is pivoted at its upper end to the rear portion 10 by means of hinges 13. The lower portion of the part 12 is secured to the member 10 by a lock 14. 15 represents a support 40 for the articles to be vended. The support 15 is secured to the part 10 of the casing by means of hinges 16. Arranged between the hinges 16 is a coil spring 17 (Fig. 1), which is adapted to throw the lower end of the support 15 forward, the object of which will be hereinafter more fully described. Sheets of paper 18 rest in the support 15, and are prevented from falling downwardly by means of pins 19 carried by said support 15 and passing through suitable openings near the upper edge of the sheets of paper 18. 20 (Figs. 3, 4, 5 and 6) is a shaft mounted in the front part of the casing, and provided with a hand-wheel 21 by means of which it may be rotated. Mounted upon the shaft 20 are a pair of semi-cylindrical members

22 having their faces roughened in any suitable manner. This is preferably accomplished by coating their surfaces with a layer 23 of emery or similar material, the object of this being to cause the surfaces of the semi-cylindrical members 22 to grip one of the sheets of paper 18, and thus tear it from its supporting pins 19. In order to hold the supports 15, and consequently the sheets of paper 18, out of contact with the members 23 during a portion of the operation of the machine I secure to the said supports 15 a pair of rack bars 24. These rack bars 24 are engaged by dogs 25, shown in detail in Fig. 3. The dogs 25 are carried upon brackets 26, secured to the part 10 of the casing. To release the dogs 25 from the rack 24 at the proper time during the operation of the machine I provide the shaft 20 with a pair of cam wheels 27, each provided with a cam face 28, adapted to strike against the inner end of one of the dogs 25. The sheet 18 detached from the support 15 by means of the members 23 is adapted to pass 80 downwardly through a slot 29 formed in the bottom of the casing at the junction of the two parts 10 and 12. To form a guide for the sheets of paper 18 I turn up the edge 30 of the part 10.

In order to control the movement of the shaft 20 I provide a coin controlled mechanism, which will now be briefly described. Formed in the part 12 of the casing is a coin chute 31, through which a coin for controlling the operation of the device is dropped. The coin after passing through the chute 31 enters a short movable chute 32 carried upon a lever 33 pivoted to a bracket 34 at 35 and projecting forwardly 95 through a slot 36. (Fig. 1.) A projection 34a carried by the bracket 34 projects below the end of the chute 32 when in its normal position. The upper part of the bracket 34 has pivoted to it a lever 37, having a lateral projection 38 and a downward projecting pin 39. The projection 38 is adapted to be engaged by coins of one size, while smaller sized coins engage with the downwardly projecting pins 39. The outer end of the lever 37 is adapted when in its normal position to be engaged with an arm 40 carried by a wheel 41, mounted upon the shaft 20. This wheel 41 also carries a number of fingers 42 adapted to engage with a star-wheel 43, mounted upon the shaft 44 of a counting device 45. The lever 37 is provided at its

end with a pair of notches 46 (Fig. 3) which are adapted to engage with the edge of a disk 47, mounted upon the shaft 20 and provided with a cut-away portion 48. The lever 37 also carries a bracket 49 adapted to bear against the star-wheel 43 and thus move it against the tension of a coil spring 50 surrounding the shaft 44 of the counting device 45. 51 represents a fixed coin chute 10 arranged below the coin chute 32 and adapted to convey the coins into the cash box 52, situated in the lower part of portion 12 of the casing. 53 is a spring attached at one end to the lever 33, hereinbefore referred to, and at the other end to a pin 54 carried by the casing 12. In order to prevent the backward rotation of the shaft 20 I secure to said shaft a ratchet wheel 55, engaged by a pawl 56, as shown in Fig. 5. 20 The operation of my device is as follows: The parts being in the position shown in Fig. 5 of the drawings, the forward layer of paper 18 will be held against the roughened surface 23 of the semi-cylindrical member 22 by the action of the coil spring 17, as the dogs 25 are moved out of engagement with the racks 24, by the action of the cams 28 on the cam wheels 27. It will, however, be impossible to rotate the hand-wheel 21, 25 because the stop 40 is in engagement with the end of the lever 37. If, however, the coin be dropped into the shaft 31 it will rest upon the projection 36, and when the outer end of the lever 33 is moved toward the right the 30 said coin will strike against either the projection 38 or 39, thus moving the front end of the lever 33 toward the right. This will cause the rear end of the said lever 33 to move toward the left out of the path of the 35 stop 40, so that the hand wheel 21, and consequently the shaft 20, may be rotated. The movement will be sufficient to bring one of the slots 46 into position to be engaged by the periphery of the disk 47, so that after 40 the movement of the shaft 20 is begun the lever 37 will be held in position until the rotation of the shaft 20 is complete. As soon as the lever 33 is released the coin will fall 45 down into the coin chute 51. As the shaft 20 is rotated the friction of the roughened faces 23 of the members 22 on the upper 50

sheet of paper 18 will tear it from its pins 19 and convey it down through the slot 29. After half a revolution of the shaft 20 is completed the hubs of the parts 22 will be held out of contact with the sheet of paper 18 as the holder 15 is locked against forward movement by the engagement of the dogs 25 with the racks 26, which engagement will take place shortly after the first movement of the shaft 20 on account of the cams 28 moving out of engagement with the dogs 25. As soon as the member 23 moves out of engagement with the sheet of paper 18, the sheet drops down through the slot 29, and if it does not drop out of the machine by its own weight it can be readily grasped by the hand and withdrawn, as there is now nothing to retain it in the machine. Upon completing the revolution of the shaft 20 the parts are again brought into their normal position and the machine is again ready for operation.

Having fully described my invention, what I claim as new and desire to secure by Letters Patent of the United States is:

1. In a vending machine, the combination with a support for the articles to be vended, of a movable member for feeding one of said articles on said supports, and means for preventing contact between said member and article while delivery of the article is completed.

2. In a vending machine, the combination with a yielding support for articles to be vended, of a movable member provided with a surface for engaging with one of said articles to move it from said support, a rack for locking said supports, and means operated by the movement of said member for releasing said rack.

3. In a vending machine, the combination with a yielding support for the articles to be vended, of a rotary member provided with a surface for engaging with one of said articles to move it from said support, a rack for locking said support, and a cam wheel operated by said rotary member to release said rack.

In testimony whereof, I have hereunto set my hand and affixed my seal.

GILBERT L. HUFF. [L. S.]
